METHOD OF MAKING TOE STIFFENERS

Filed Dec. 17, 1923

Inventor:
Evans P. Carr,

Frank D. Parker
Atty.

UNITED STATES PATENT OFFICE

EVANS P. CARR, OF ROCHESTER, NEW YORK

METHOD OF MAKING TOE STIFFENERS

Application filed December 17, 1923. Serial No. 681,152.

The invention relates to improvements in the manufacture of box toe or box toe material, and more particularly to the method of making the same.

5 A well known step in the art consists in coating or saturating a piece of fabric to be interposed between the vamp lining and tip lining of shoes and boot caps, with a solution of celluloid, and to unite the parts while still 10 wet. This procedure has the great disadvantages that each stiffener must be treated individually on either side with the celluloid, which requires careful handling, time for doing so, and waste.

15 The object of the present invention is to eliminate the above disadvantages, and therefore in this particular, there is used a liquid celluloid or any of its variations or bases, such as pyralin, pyroxylin, parkesine, etc., for 20 a box toe preparation to be used in the following manner.

A suitable size piece of fabric, adaptable for making a determined number of box toes or box toe material, is coated with the above 25 indicated preparation, whereupon this coated fabric is left to become almost dry, and a thin piece of fabric is then placed over said coated face of the first-mentioned piece of fabric. On the assembly of the several pieces of fabric with the coating therebetween, the unit 30 is then passed between heated rolls to remove wrinkles from the fabric, and thus rendered smooth, which latter is thereafter dried thoroughly. The materials thus treated are cut 35 into suitable sizes and shapes for use as a box toe or box toe stiffener in boots and shoes.

The sized and shaped box toe blanks are now soaked in a suitable softener until the same become soft and pliable, then they are 40 put into an air tight receptacle, which will maintain them in suitable temper for subsequent use, the receptacle being of a character to assure the blanks of a soft and pliable 45 condition for six to eight hours. The toe blanks thus treated will be taken from the receptacle as needed by an operator and properly placed in the toe of a boot or shoe upper prior to the lasting thereof. Now when the 50 operator pulls the upper over the last the

softened solution will be caused to ooze through the fabric at both sides of the blank and thereby soak the lining and toe lining of the boot or shoe, and on the drying of the fabric and linings there will be present a hard 55 yet pliable box toe, and thoroughly waterproof.

The thin piece of fabric placed over the coated fabric at its coated side will keep the coating from running while being softened 60 and prevent the solution on the softening thereof from soiling the hands of the operator, thereby avoiding the possibility of the latter staining the boots or shoes in the formation thereof, which would otherwise be the result 65 should the coating substance get upon the hands, as it is extremely sticky. It is of course understood and known that an operator has to catch hold of the upper of the boot or shoe immediately after placing the box toe blank 70 in position, to guide it in the machine, so he would have no chance to wipe the sticky solution from his fingers should the same get thereon.

With the above and other objects in view, 75 the invention consists in the features of construction, combination and arrangement of parts as will be hereinafter more fully described, illustrated in the accompanying drawing, and pointed out in the claims hereunto 80 appended.

In the accompanying drawings:

Figure 1 is a plan view of a toeboxing or stiffener constructed and treated in accordance with the invention.

Figure 2 is a sectional view thereof.

Similar reference characters indicate corresponding parts throughout the several views in the drawings.

Referring to the drawing, in detail, A, designates generally the base fabric, preferably canvas, although any other suitable fabric material may be used, and upon one face of this fabric is applied in any desirable manner a liquid celluloid or one of its variations or bases—although any stiffener which can be coated onto a suitable covering, dried and softened again by means of a suitable solvent may be used—as indicated at B, but preferably pyralin, pyroxylin or nitro-cellu- 95 100

lose in combination with any suitable solvent such as acetone, anyl-acetate is employed.

The fabric A, with the coating B, is left to stand until the coating is almost dry, then a thin piece of cloth C, of any suitable material, is placed over said coating, whereupon the united fabrics are passed between heated rolls to remove all wrinkles therefrom and thus render the same smooth. After the fabrics in their united form have become thoroughly dried, the treated material is to be cut into suitable sizes and shapes for use as a box toe stiffener, in boots and shoes. In the cutting of the thin cloth C, the edge 5, thereof is inset from the edge 6, of the fabric A, whereby the latter will extend beyond said cloth C, thereby eliminating a ridge at the tip line of the boot or shoe when the stiffener or boxing has been placed therein.

On the cutting of the material treated in the size and shape as exemplified in Figure 1, of the drawing, the blank is soaked in a suitable softener until it becomes soft and pliable, then taken out and put into an air-tight container or receptacle, which will keep it in suitable temper for a period of from six to eight hours.

The blanks are taken from the container or receptacle as needed by an operator and put in proper place in the toe of a boot or shoe upper. When subjected to pressure in pulling the upper over a last, the softened solution will ooze through both pieces of fabric of the blank and soak the lining and tip lining of the boot or shoe and the whole after drying will become a hard yet pliable box toe. The box toe when hard will be absolutely waterproof.

As has been stated the thin cloth piece put over the coating in the first instance will keep the coating from running while being softened and prevent the solution when soft from soiling the hands of the operator.

It is known that a cloth coated or saturated with a celluloid solution is now in use, but the article herein described is coated in such a manner and with a solution so thick that only the slightest amount appears on the other side of the cloth and the coating is allowed to partially dry before putting on the cloth that covers it, so that no solution can saturate the same. The unit when softened is effected in such manner that the solution is not allowed to become soft enough to saturate the cloth coverings or fabrics at opposite sides of the coating, the pressure from lasting the upper over the last being depended upon to force the solution through the cloth and into the lining of the shoe or boot.

The box toe material treated as heretofore is to be made in the form of sheeting and cut into box toe blanks afterwards.

The cloth or fabric or other material used for covering the stiffener may be cut into proper size and shape for the box toe blanks

before the stiffener is applied, if so desired. The preparation or stiffener is then applied to one cover and after allowing the same to set for a few minutes the other cover is placed over the preparation. The made box blank is then immediately placed in an air tight compartment and after being allowed to set may be taken out and placed in proper position in toe of upper without dipping it in the softening solution.

What is claimed is:

The herein described method of making box toe stiffeners, which consists in coating a fabric with a celluloid solution; allowing the coating to become partially dry; spreading a thin fabric over the coating; running the composite material through heated rolls to smooth out the wrinkles; allowing the smoothed material to become thoroughly dried; cutting out the stiffeners; and soaking them in a softener when required for use.

In testimony whereof I affix my signature.

EVANS P. CARR.
